CLAIM

The ornamental design for a wood/bamboo container lid, as shown and described.

DESCRIPTION

FIG. 1 is a top perspective view of a wood/bamboo container lid showing our new design;

FIG. 2 is a bottom perspective view thereof;

FIG. 3 is a front elevation view thereof;

FIG. 4 is a rear elevation view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is a bottom perspective view thereof showing a container of the environment.

The broken lines a container are for the purposes of illustrating environment and form no part of the claimed design.
